Inventor:
A. G. McKee,
A. G. McKee,
his Attorney

UNITED STATES PATENT OFFICE.

ARTHUR G. MCKEE, OF CLEVELAND, OHIO.

BELL-OPERATING MECHANISM FOR BLAST-FURNACES.

1,288,948.

Specification of Letters Patent. Patented Dec. 24, 1918.

Application filed May 27, 1916. Serial No. 100,372.

To all whom it may concern:

Be it known that I, ARTHUR G. MCKEE, a citizen of the United States, resident of Cleveland, county of Cuyahoga, and State 5 of Ohio, have invented a new and useful Improvement in Bell-Operating Mechanism for Blast-Furnaces, of which the following is a specification, the principle of the invention being herein explained and the best 10 mode in which I have contemplated applying that principle, so as to distinguish it from other inventions.

My invention relates to blast-furnace charging-devices and particularly to that 15 class of the latter which includes two hopper controlling co-axial bells.

The broad object of the invention is to provide a construction in the above-described class of charging apparatus, where- 20 by after any dislocation of the parts, due to settling of foundations or otherwise, it may be readily and economically corrected or compensated for and a continued uniformity of distribution of the charge be thus secured.

25 The said invention consists of means hereinafter fully described and particularly set forth in the claims.

The annexed drawings and the following 30 description set forth in detail certain means embodying my invention, the disclosed means, however, constituting but one of various mechanical forms in which the principle of the invention may be applied.

In said annexed drawings:-

35 Figure 1 represents a side elevation of the upper part of a blast furnace charging apparatus of the above-mentioned type, together with the top of the blast furnace itself, to which my invention has been applied, 40 such blast furnace top and the hoppers, as well as other parts, being shown in vertical axial section.

Fig. 2 represents a plan of the parts shown in Fig. 1.

45 Fig. 3 represents a side elevation, upon an enlarged scale, of the actuating mechanism, showing the parts in a different position from that which they are shown as occupying in Fig. 1.

50 Fig. 4 represents a plan of such actuating mechanism upon an enlarged scale.

Fig. 5 represents a side elevation of the parts shown in Fig. 4 and on a similar scale.

Fig. 6 represents a vertical section taken

upon the plane indicated by a line VI—VI 55 in Fig. 5.

Fig. 7 represents a vertical section taken upon the planes indicated by lines VII—VII 60 in Fig. 5 and viewed in the direction indicated by the arrows.

Fig. 8 represents a horizontal section taken upon the plane indicated by line VIII—VIII 65 in Fig. 6 and viewed in the direction indicated by the arrows.

Fig. 9 represents a section taken upon the 70 plane indicated by line IX—IX in Fig. 5 and viewed in the direction indicated by the arrows.

Fig. 10 represents a vertical section taken upon the plane indicated by the line X—X 75 in Fig. 5.

The type of blast furnace charging apparatus which is illustrated in the drawings and to which the illustrated embodiment of my invention is shown to be applied, is of 75 well-known construction and previously patented by me.

In this type of apparatus, the upper part or top of the blast furnace 1 is provided with a cylindrical hopper 2 whose lower and 80 discharging opening 3 is closed by a conical bell 4 suspended from a rod 5.

Mounted upon the top of this hopper 2 is a second hopper 6 vertically co-axial with the hopper 2 whose lower or discharging 85 opening 7 is closed by a smaller and co-axial bell 8 suspended from a hollow rod 9 through whose interior the rod 5 extends upwardly. Suitably mounted upon the super-structure 10 is a receiving spout 11 provided 90 with a lateral opening 12 which directly receives the several constituent parts of the charge, as is well known to those skilled in the art.

The above described apparatus contem- 95 plates first, the even distribution of the successive constituent parts of the charge in the hopper 2 through the medium of the hopper 6 and then the even distribution of the ac- cumulation of the different parts of the charge in the said hopper 2 in the blast fur- nace, all as is also well known to those skilled in the art. However, to effect this desired result, it will be seen that it will be neces- 100 sary to always maintain co-axiality between 105 the hoppers 2 and 6 and the bells 4 and 8, so that when these bells are lowered away from their respective openings, a true annular

space will be formed so as to permit a uniform discharge downwardly of the material above the bells opposite all points of the peripheries of the latter.

5 I have found that in some cases, this coaxiality is disturbed either as a result of contraction or expansion of the parts or by settling of the foundations, so that the true character of the annuli also is disturbed and 10 such uniformity of distribution, in consequence, is not obtained.

In order, therefore, to provide suitable mechanism for actuating these bells to open and close as may be required, and at the 15 same time to permit of a ready re-alinement or restoration of co-axiality of these bells and their respective hoppers, I have provided a peculiar construction and arrangement of parts which I shall now proceed to 20 describe.

The superstructure 10 supports a platform 13 in the usual manner. Mounted upon this platform is a frame-structure 14 shown in detail in Figs. 3, 4, 5, 6, 7 and 10 25 respectively. This frame-structure comprises a lower plate 15 which is preferably secured to the platform by means of suitable nuts and bolts (not shown). Resting upon and suitably secured to this plate are two 30 I-beams 16, 16, Figs. 4, 6, 7 and 10, to which are secured upright members 17. These upright members carry two I-beams 19 parallel with the I-beam 16 which latter are placed so as to extend, as shown, in a direction perpendicular to a vertical transverse plane passing through the axis of the hoppers. Resting directly upon the lower I-beam 16 is a cylinder 20 having secured thereto suitable guides 21 for a cross-head 40 22. This cross-head has attached thereto a piston rod 23 which is connected in the usual manner with a piston (not shown). Supported by and suitably secured to the upper I-beams 19 is a second but smaller 45 cylinder 24 also provided with guides 25 which receive a cross-head 26 attached to a piston rod 27 connected with a suitable piston (not shown). These two cylinders are parallel and have their axes extending in a 50 direction perpendicular to the aforementioned plane, as will be observed.

Suitable additional members are provided for properly bracing and otherwise strengthening this frame-structure.

55 These two cylinders, it will be observed, are both located upon the same side, the right side as shown in Fig. 1, of said plane.

Secured to said frame-structure and forming a part thereof, are two standards 60 28 formed with suitable bearings for receiving an axle 29 upon which is mounted a bell-crank 30 having two upper arms 31 and a single lower arm 32 connected with cross-head 26 by means of a connecting-rod 65 31a. The two arms 31 are respectively con-

nected with two depending rods 33 whose lower ends are secured to a hollow suspending rod 9 by means of a suitable coupling 34, to whose lower end is attached the bell 8, as clearly shown in Figs. 1 and 6. A suitable counterweight 35 is secured to the bell-crank 30, as shown in Figs. 4 and 5.

Suitable valves and steam connections (not shown) are provided for actuating the piston in the cylinder 24, whereby the bell-crank may be oscillated and the bell 8 raised or lowered as may be desired, all as will be readily understood by those skilled in the art.

As shown, the frame-structure extends beyond the aforementioned plane, and upon that part of such structure so extending there is mounted in suitable bearings, an axle 36 to which is fixed a second bell-crank 37 having an upper arm 38 and a lower arm 39. This lower arm is connected with a connecting rod 40 connected with the cross-head 22. The upper arm is connected with the upper end of a link 41 whose lower end is connected with one end of two link bars 42 whose other ends have a fixed axis 43 upon a suitable part of the frame-structure such as an I-beam 18, as shown in Figs. 3 and 5. These link arms are made of the same length as the arm 38 of the bell-crank, 95 and from the middle of the link 41 are suspended two downwardly extending suspension bars 44 whose lower ends are attached to cross-head 45, the latter acting as a guide for the bars 33, as shown in Fig. 6. Secured 100 to the cross-head is the upper end of the previously mentioned suspending rod 5 whose lower end is attached to the bell 4, as shown in Fig. 1.

The arrangement of the bell crank 37, 105 link bars 42 and link 41 is such, as will be seen, that it provides what is known as "parallel-motion" so that the upper ends of the bars 44 travel substantially in a right line. A suitable counterweight 46 is secured 110 to the bell-crank 37.

Suitable valves and steam connections are provided for the cylinder 20 as in the case of the cylinder 24, so that the bell 4 may be, in consequence, raised and lowered when 115 desired and independently of the bell 8.

From the above description, it will be seen that the means actuating, that is, raising or lowering the bells, include two suspending members, one for each bell, two 120 motor members and means connecting the latter with such suspending members. The hollow rod 9 and the suspending rods 33, constitute the suspending member for the bell 8, whereas the rod 5, together with the 125 bars 44 and cross-head 45, form the suspending member for the bell 4. The bell-cranks and the parts immediately connected therewith, constitute the means for connecting the motor members or cylinders with the 130

suspending members. It will also further be noted that all of these described means are mounted upon a common support or frame-structure and it will therefore be seen 5 that a shifting of the position of this frame-structure will also effect a shifting of the position of all of these named parts.

The hoppers 2 and 6 being fixed with relation to each other, any dislocation of the 10 superstructure and hence the parts connected therewith, including the points from which the bells are suspended, which may occur with reference to one hopper, will also occur with reference to the other. As 15 a result, as the bells open, they would assume a position eccentric with reference to the openings in the respective hoppers. In the event, therefore, that such dislocation should take place, and the co-axiality of the 20 bells and hoppers destroyed, it will be seen that by disconnecting the frame-structure from the platform 13, such frame-structure, together with all the parts, may be shifted into a new position and one which will re- 25 establish such co-axiality, after which the frame-structure is again suitably secured to the platform.

In this manner, therefore, it will be seen that the required correction may be readily 30 and economically effected so as to reestablish a uniform action of the bells in so far as it relates to the distribution of the charge previously referred to.

Having fully described my invention, 35 what I claim and desire to secure by Letters Patent is:—

1. In bell-operating mechanism for blast furnace charging devices, the combination of a furnace top; a pair of hoppers mounted 40 thereon; hopper controlling bells; separate means for raising and lowering said bells including suspending members, two motor members, and means connecting the latter with said suspending members and including 45 a parallel motion; and a framework mounted upon said furnace top, horizontally adjustable relatively thereto, and supporting both of said raising and lowering means.

2. In bell-operating mechanism for blast 50 furnace charging devices, the combination of a furnace top; a pair of hoppers mounted thereon; hopper controlling bells; separate means for raising and lowering said bells including suspending members, two motor 55 members disposed in planes perpendicular to the plane containing the axis of said hoppers, and means connecting the motor members with said suspending members and including a parallel motion; and an adjustable framework mounted upon said furnace 60 top for supporting said raising and lowering means.

3. In bell-operating mechanism for blast 65 furnace charging devices, the combination with a furnace top; of a superstructure

mounted thereon, a hopper and a hopper controlling bell, means for raising and lowering said bell including a suspending member, a motor member and means connecting the latter with said suspending member, and 70 a common frame structure adjustably mounted upon said superstructure and upon which said motor member, connecting means, and suspending member are all mounted, said motor member being offset 75 with relation to said suspending member.

4. In bell-operating mechanism for blast furnace charging devices, the combination with a furnace top; of a superstructure mounted thereon, a pair of hoppers mounted 80 upon said top, hopper controlling bells, separate means for raising and lowering said bells including suspending members, motor members and means respectively connecting the same with said suspending members, 85 and a common frame structure adjustably mounted upon said superstructure and upon which said motor members, connecting means, and suspending members are all mounted, said motor members being offset 90 with relation to said suspending members.

5. In bell-operating mechanism for blast furnace charging devices, the combination of a suitable main support; a frame structure mounted thereon; two hoppers and hopper controlling bells; two suspending members respectively connected with the latter; two cylinders with pistons, piston-rods, guides, cross-heads and connecting rods therefor, all mounted upon said frame structure; bell-crank mounted upon said frame structure, connected with said piston rods, respectively, and located, respectively, upon the two sides of a plane passing through the axis of said hoppers; and means connecting said bell-crank with said suspending members, respectively. 100

6. In bell-operating mechanism for blast furnace charging devices, the combination of a suitably mounted support; a frame structure mounted thereon; two hoppers and hopper controlling bells; two suspending members respectively connected with the latter; two cylinders with pistons, piston rods, guides, cross-head and connecting rods 110 therefor, all mounted upon said frame structure; bell cranks mounted upon said frame structure, connected with said piston rods, respectively, and located, respectively, upon the two sides of a plane passing through the 115 axis of said hoppers; and means including a parallel motion connecting said bell cranks with said suspending members, respectively. 120

7. In bell-operating mechanism for blast furnace charging devices, the combination 125 of a suitably mounted support; a frame structure adjustably mounted thereon; two hoppers and hopper controlling bells; two suspending members respectively connected with the latter; two cylinders with pistons, 130

piston rods, guides crossheads and connecting rods therefor, all mounted upon said frame structure; bell cranks mounted upon said frame structure, connected with said 5 piston rods, respectively, and located, respectively, upon the two sides of a plane passing through the axis of said hoppers; and means connecting said bell cranks with said suspending members, respectively.

10 8. In bell-operating mechanism for blast-furnace charging-devices, the combination of a suitable main support; a frame-structure mounted upon and suitably secured to the latter; two hopper controlling bells; two suspending members respectively, connected with the latter; two hoppers and horizontal cylinders with pistons, piston-rods, guides, cross-heads and connecting-rods therefor, all mounted upon said frame-structure, the one 15 cylinder being mounted above the other; a bell-crank mounted upon said frame-structure connected with one of said piston-rods and located upon one side of a plane passing through the axis of said hoppers and perpendicular to the direction of movement of said pistons; a second bell-crank located upon the other side of said plane and connected to the 20 other of said piston rods; and means connecting said bell-cranks with said suspending members respectively, also mounted upon said frame-structure.

25

connected to the other of said piston rods; and means connecting said bell-cranks with said suspending-members respectively. 30

9. In bell-operating mechanism for blast-furnace charging-devices; the combination of a suitable main support; a frame-structure mounted upon and suitably secured to the latter; two hopper controlling bells; two suspending members respectively connected with the latter; two hoppers and horizontal cylinders with pistons, piston-rods, guides, cross-heads and connecting-rods therefor, all mounted upon said frame-structure, the one 35 cylinder being mounted upon the other; a bell-crank mounted upon said frame-structure connected with one of said piston-rods and located upon one side of a plane passing through the axis of said hoppers and perpendicular to the direction of movement of said pistons; a second bell-crank located upon the other side of said plane and connected to the other of said piston rods; and means connecting said bell-cranks with said suspending members respectively, also mounted upon 40 said frame-structure. 45

Signed by me this 17th day of May, 1915,
ARTHUR G. MCKEE.
